UNITED STATES PATENT OFFICE.

JOSEPH S. DUNCAN, OF CHICAGO, ILLINOIS.

FOLLOWER FOR FILING DRAWERS.

Application filed February 9, 1922. Serial No. 535,152.

To all whom it may concern:

Be it known that I, JOSEPH S. DUNCAN, a citizen of the United States, residing at Chicago, in the county of Cook and State of Illinois, have invented certain new and useful Improvements in Followers for Filing Drawers, of which the following is a specification.

This invention has for its object to provide a strong and substantial follower for filing drawers which can be easily moved to adjusted position and then locked securely to support cards, files or other material in a desired manner.

And a further object of the invention is to provide an efficient lock for securely holding the follower in adjusted position so that it will not yield to the pressure of the cards, files, or other material supported thereby in the drawer, but which can be easily and quickly released to permit readjustment of the follower.

In the accompanying drawings I have illustrated a selected embodiment of the invention, and referring thereto—

Fig. 1 is a longitudinal sectional view of a drawer equipped with my improved follower;

Fig. 2 is a transverse sectional view on the line 2—2 of Fig. 1;

Fig. 3 is a sectional view on the line 3—3 of Fig. 2;

Fig. 4 is a sectional view on the line 4—4 of Fig. 1; and

Fig. 5 shows the follower in locked position.

I have illustrated the invention in a drawer adapted for holding cards of a card system, but it will be understood that the invention may be employed in larger drawers for holding files or other material. The drawer 6 is shown made of metal with a flange 7 depending from the upper edge of each side wall and spaced therefrom to form channels 8.

The follower comprises a body member 9 which has a centrally disposed upstanding projection 10 forming a handle or finger-piece to facilitate adjustment of the follower. The ends 11 of the body member are bent to lie substantially parallel with the side walls of the drawer and they are adapted to slide on the bottom 12 of the drawer and within the channel guide formed of the overhanging flanges 7. A bow spring 13 is mounted on each end 11 and engages the

top wall 14 of the channel and the ends of the spring are bent at 15 and engage with holes 16 in the end. The springs will restrain the follower against free movement in the drawer when it is not locked and they also hold the follower in upright position, as shown in Fig. 1. The upper forward corner of each end 11 is inclined at 17 so that the follower may be tilted backward until the inclined edges 17 engage the top wall 14 of the channels, to facilitate inspection of the cards in the drawer and the insertion or removal of the cards.

The body member is also provided with upstanding bearing projections 18 located adjacent to the opposing faces of the depending flanges 7, 7. Levers 19 are pivoted at 19' on the body member and carry jaws 20 which project upward into the channels 8. A lug 21 on one lever projects over the upper edge of the other lever and forms a bearing for a cam lever 22 which is pivoted at 22' to the body member. A stop 23 on the body member limits the opening movement of the cam lever and a lug 22' on the cam lever is arranged to engage one of the jaw levers. The projections 18 are bent at 18' to form bearings disposed opposite the jaws, as shown in Fig. 3.

In the form illustrated both the drawer and the follower are made out of sheet metal and the parts can be very accurately cut or stamped to fit closely without interfering with the adjustment of the follower. In practice, the follower is free to move when the locking lever is in upright position, as shown in Fig. 2. After the follower has been adjusted to desired position the locking lever is swung down to horizontal position, thereby depressing the overlapping ends of the jaw levers and forcing the jaws inward and clamping the flanges 7 between themselves and the bearing projections 18. Thus the follower is locked in its adjusted position in the drawer and this locking is sufficiently secure for all purposes because of the extended engaging surfaces where the jaws clamp the flanges against the bearing projections and the leverage afforded by the levers 19. When the locking lever is swung to open upright position the jaws will be sufficiently released to enable the free adjustment of the follower.

I reserve the right to make all such changes in the form, construction and proportion of parts of the invention herein dis-

closed, and to vary the materials, as may be required for different purposes, so far as the same fall within the scope of the following claims, and I desire to have it understood that the form of the invention herein shown and described is merely one of a number within the scope of the invention.

I claim:

1. A follower for filing drawers comprising a body member having upstanding bearing projections, levers pivotally mounted on the body member at the base of said projections, clamping jaws on said levers extending upward in cooperative relation with said projections, and means for operating the levers.

2. The combination of a drawer having flanges on its side walls, a follower adapted to slide in said drawer and comprising a body member, jaws pivotally mounted on said body member and operating between the flanges and the side walls of the drawer to clamp said flanges between themselves and portions of the body member, and means for operating said jaws.

3. The combination of a drawer having flanges on its side walls, a follower adapted to slide in said drawer and comprising a body member, levers pivotally mounted on

said body member and having jaws operating between the flanges and the side walls of the drawer to clamp said flanges between themselves and portions of the body member, and means for operating said levers.

4. The combination of a drawer having flanges on its side walls, a follower adapted to slide in said drawer and having upstanding projections adjacent said flanges, levers pivotally mounted on the follower and having jaws projecting into the spaces between the side walls and the flanges of the drawer to clamp the flanges between themselves and said projections, and means for operating said levers.

5. The combination of a drawer having flanges on its side walls, a follower adapted to slide in said drawer and having upstanding projections located adjacent to and between said flanges, horizontally disposed levers pivotally mounted on the follower and having jaws projecting upward into the spaces between the side walls and the flanges to clamp the flanges between themselves and said upstanding projections, and means on the follower to engage and operate said levers.

JOSEPH S. DUNCAN.
